UNITED STATES PATENT OFFICE

2,358,601

PRESSURE FLUID MOTOR

Frank E. Sinclair, Claremont, N. H., assignor to
 Sullivan Machinery Company, a corporation of
 Massachusetts

Application July 23, 1940, Serial No. 346,939

7 Claims. (Cl. 121—18)

This invention relates to pressure fluid motors, and more particularly to improvements in the fluid distribution means of a pressure fluid motor of the reciprocating piston type.

An object of this invention is to provide an improved pressure fluid motor. Another object is to provide an improved fluid distribution means for a pressure fluid motor wherein improved distributing valve means is employed for controlling the flow of pressure fluid to the motor cylinder. A further object is to provide an improved fluid distributing valve for a pressure fluid motor, having improved means for throwing the valve into its different operating positions. Still another object is to provide an improved fluid distributing valve mechanism having improved throwing means whereby the distributing valve is thrown a substantial interval prior to the opening of the cylinder exhaust. A still further object is to provide an improved pressure fluid motor of the long stroke, reciprocating piston type, having improved fluid distribution means. Yet another object is to provide an improved fluid actuated, fluid distributing valve and improved throwing passage means associated therewith. These and other objects of the invention will, however, hereinafter more fully appear.

In the accompanying drawing there is shown for purposes of illustration one form which the invention may assume in practice.

In this drawing:

Fig. 1 is a central, longitudinally extending, vertical sectional view through a pressure fluid motor constructed in accordance with the illustrative embodiment of the invention.

Fig. 2 is a sectional view similar to Fig. 1, showing the distributing valve and motor piston in different positions.

Fig. 3 is an enlarged end elevational view of the improved fluid distributing valve.

In this illustrative embodiment of the invention there is shown a pressure fluid motor of the reciprocating piston type especially designed for use in impact tools, such as pavement breakers. It will be evident, however, that features of the invention may be embodied in pressure fluid motors of various other types.

The pressure fluid motor disclosed herein comprises a motor cylinder 1 having an elongated bore 2 containing a reciprocating hammer piston 3. The motor cylinder has a front head 4 having an axial bore 5 in which a tappet 6 is mounted for reciprocating movement. This tappet projects within the forward end of the cylinder bore in the manner shown, in a position to receive

the impact blows of the motor piston and to transmit such blows to the shank 7 of a working implement, such as a conventional pick point or the like. The motor cylinder has a rear head plate 8, and interposed between the head plate and a rear head block 9 is a valve block 10. The head block 9 has a bore 11, and the head plate, valve block and the rearward portion of the motor cylinder are fitted within the head block bore in the manner shown. The front head 4 and the rear head block 9 may be secured to the motor cylinder in any suitable manner.

Now referring to the improved fluid distributing means, it will be noted that formed within the head plate 8 and valve block 10 is a valve chamber 12 in which a distributing valve 13 of the flanged sleeve type is reciprocably mounted. The head plate and the valve block have aligned uniform bores 14 and 15 respectively, and the valve has a cylindric sleeve-like body 16 slidably fitted within these bores. Formed externally on the valve body midway between its ends is an annular flange 17 adapted to seat at its opposite faces against plane seating surfaces 18 and 19 on the head plate and valve block respectively. The valve flange 17 is arranged within an annular recess 20 provided by end bores 21 and 22 in the head plate and valve block respectively and an annular space between the head plate and valve block. Pressure fluid may be supplied to the annular recess 20 from any suitable source through a passage 23 communicating with a chamber 24 formed in the rear head block 9, and through a series of passages 25 connecting the chamber 24 with the annular recess 20. Communicating with the bores 21 and 22 at the opposite sides of the external valve flange 17 are annular grooves 26 and 27 respectively. The sleeve-like valve body 16 has transverse partitions 28 spaced from its ends to provide end recesses 29, and the valve is made hollow at 30 between these partitions for the purpose of lightness. For further lightening the valve, the opposite faces of the external valve flange 17 are annularly recessed at 31. Fluid distribution passages 32 communicate with the groove 27 at the rear face of the external valve flange 17, and ports 33 connect these passages with the forward end of the cylinder bore. A series of fluid distribution passages 34 connect the groove 26 at the forward face of the external valve flange with the rear end of the cylinder bore. The motor cylinder is provided with piston-controlled exhaust passages 35 arranged substantially midway between the ends of the cylinder bore and controlled by the

motor piston. Communicating with the cylinder bore at longitudinally spaced points respectively at the opposite sides of the exhaust passages 35 are ports 36 and 37, and these ports are connected by passages 38 and 39 respectively with the opposite ends of the valve chamber at the opposite sides of the distributing valve, the passage 38 communicating with the forward end of the bore 14 through a port 40, and the throwing passage 39 communicating with the rear end of the bore 15 through a port 41. Restricted passages 42 and 43 connect the annular supply recess 20 with the passages 38 and 39 respectively. The cross sectional areas of the restricted leak passages 42 and 43 are such that the flow of fluid therethrough to the passages 38 and 39 respectively is not sufficient to maintain, when the cylinder ends of passages 38 and 39 are uncovered, a much higher pressure in the ends of the valve chamber at the opposite ends of the valve body than exists in the cylinder bore where the passages 38 and 39 communicate with the latter; so that when the passages 38 and 39 are connected to exhaust through the ends of the cylinder bore under the control of the motor piston, a large reduction in the pressure acting on the ends of the valve body occurs, as will later be explained. Also when the cylinder pressure falls because the rate of admission is insufficient to maintain it at line pressure, the pressure at an end of the valve will be reduced when connection with the cylinder is established. The valve is guided solely at the exterior periphery of the cylindric sleeve-like body 16, and there is a slight clearance at 44 between the exterior periphery of the external valve flange 17 and the walls of the bores 21 and 22, and this restricted clearance provides restricted clearance spaces 45 and 46 between the exterior of the external valve flange and the walls of the bores 20 and 21 for the purpose of metering the flow of pressure fluid from the annular supply recess 20 past the distributing valve to the ends of the cylinder bore.

The mode of operation of the improved pressure fluid motor is as follows. When the distributing valve 13 is in the position shown in Fig. 1 and pressure fluid is supplied from the passage 23 through chamber 24 and passages 25 to the annular supply recess 20, pressure fluid may flow from the supply recess 20 through the restricted clearance space 45, through the valve chamber 12 past the forward face of the external valve flange 17 and through groove 26 and distribution passages 34 to the rear end of the cylinder bore. The pressure fluid acting on the rear pressure area of the motor piston 3 moves the latter forwardly to effect its working stroke, i. e. to deliver an impact blow to the tappet 6. When the motor piston starts its forward movement from the position shown in Fig. 1, the forward end of the cylinder bore is connected to exhaust and the rear surface of the valve body and a portion of the rear face of the external flange are connected to exhaust through the passages 35 and 32 respectively. As the motor piston moves forwardly, the leading edge of the piston first overruns the exhaust passages 35, thereby to cut off the front end of the cylinder bore and the rear valve surfaces from the exhaust. Upon continued forward piston movement, the leading edge of the piston overruns the port 37 of the passage 39, and thereafter the following edge of the piston uncovers the port 36 of the passage 38, thereby connecting the forward end of the bore 14 at the forward side of the valve body to the rear end of the cylinder

bore, and as a result, the pressure in the valve chamber at the forward side of the valve body is substantially reduced. When the port 37 of the passage 39 is covered by the motor piston, the pressure fluid leaking through the restricted passage 43 to the passage 39 flows through the port 41 to the rear end of the valve chamber at the rear end of the valve body to act on the effective rear pressure area of the valve body. As the motor piston continues to move forwardly, the pressure fluid trapped within the forward end of the cylinder bore is compressed, and this compression pressure is transmitted through the ports 33, distribution passages 32 and annular recess 21 to the bore 22 at the rear side of the external valve flange, and this compression pressure acts on the exposed rear pressure area of the external valve flange to supplement the pressure leaking through the passage 43, thereby to throw the valve forwardly from the position shown in Fig. 1 to the position shown in Fig. 2. The pressure fluid leaking through the passage 43 to the passage 39 and through the port 41 to the rear end of the valve chamber at the rear side of the valve body acts on the effective rear pressure area of the valve body to hold the valve in its foremost position. After the valve is thrown, the piston continues to move forwardly, and as the motor piston approaches the forward end of its stroke, its following edge uncovers the exhaust passages 35, connecting the rear end of the cylinder bore to exhaust, and the motor piston thereafter delivers its impact blow to the tappet. When the valve is in the position shown in Fig. 2, pressure fluid may flow from the annular supply recess 20 through the restricted clearance space 46, through the valve chamber 12 past the rear face of the external valve flange and through annular recess 21 and distribution passages 32 and ports 33 to the forward end of the cylinder bore, the pressure fluid acting on the forward pressure area of the motor piston to move the latter rearwardly to effect its return stroke. When the motor piston starts its rearward movement from the position shown in Fig. 2, the rear end of the cylinder is connected to exhaust, and the front surface of the valve body and a portion of the front face of the external flange are connected to exhaust through passages 38 and 34 respectively. As the motor piston moves rearwardly, its leading edge first overruns the exhaust passages 35 and thereafter overruns the port 36 of the passage 38, and upon continued rearward piston movement the following edge of the piston uncovers the port 37. When the port 37 is uncovered by the following edge of the piston, the rear end of the bore 15 at the rear side of the valve body is connected through port 41, passage 39 and port 37 with the front end of the cylinder bore, and as a result, the pressure in the valve chamber at the rear side of the valve body is substantially reduced. When the port 36 of the passage 38 is covered by the motor piston, the pressure fluid leaking through the restricted passage 42 to the passage 38 flows through the port 40 to the front end of the valve chamber at the front end of the valve body to act on the effective front pressure area of the valve body. As the piston moves towards the rear end of the cylinder, the pressure fluid trapped within the rear end of the cylinder bore is compressed, and this compression pressure is transmitted through the distribution passages 34 and the groove 26 to the bore 21 at the front side of the external valve flange to supplement the pressure leaking

through the passage 42, thereby to throw the valve rearwardly from the position shown in Fig. 2 to the position shown in Fig. 1. The pressure fluid leaking through the restricted passage 42 through the port 40 to the front end of the valve chamber at the forward side of the valve body acts on the forward pressure area of the valve body to hold the valve in its rearmost position. Upon continued rearward piston movement, the following edge of the piston uncovers the exhaust passages 35, connecting the front end of the cylinder bore to the exhaust. The operations above described are rapidly repeated during normal running of the motor.

As a result of this invention it will be noted that an improved pressure fluid motor is provided having improved fluid distribution means which is not only simple in design but also extremely efficient. It will also be evident that by the provision of the improved valve throwing means for the valve the latter is thrown in an improved manner, resulting in a motor which is not only efficient but is also extremely rapid and powerful in operation. Other uses and advantages of the improved fluid distribution means will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a pressure fluid motor, the combination comprising a cylinder having a bore, a piston reciprocable therein, a piston-controlled exhaust for said cylinder bore, means providing a valve chamber, distribution passages leading from said chamber respectively to the opposite ends of said cylinder bore, a pressure fluid supply, a fluid actuated fluid distributing valve movably mounted in said valve chamber for alternately connecting said distribution passages with said supply, relatively restricted passage means for continuously supplying live pressure fluid to equal opposed pressure areas on said valve, pressure reducing passages connected to the cylinder bore at points each spaced longitudinally of the cylinder bore a substantial distance with respect to said cylinder exhaust and controlled by said piston for alternately connecting said opposed pressure areas to the cylinder bore to effect a reduction in the pressure acting on said areas, and means for alternately subjecting other opposed pressure areas on said valve to compression pressure built up by the piston in the ends of said cylinder bore, whereby said valve is thrown during each piston stroke a substantial interval prior to the opening of the cylinder bore exhaust.

2. In a pressure fluid motor, a cylinder having a bore, a piston reciprocable therein, and fluid distribution means for supplying pressure fluid to and exhausting fluid from said cylinder bore for effecting reciprocation of said piston including an automatic pressure fluid actuated fluid distributing valve, passage means controlled by said valve for supplying pressure fluid to the opposite ends of said cylinder bore, an exhaust port for said cylinder bore overrun by said piston, and means for throwing said valve a substantial interval prior to the opening of the cylinder exhaust dur-

ing each piston stroke including a pressure area on each end of said valve and relatively restricted passage means for supplying pressure fluid from a relatively constant pressure source to each of said pressure areas, exhaust passages communicating with said pressure areas and opening into said cylinder bore at opposite sides of said exhaust port at points each spaced longitudinally of the cylinder bore a substantial distance from said exhaust port, said exhaust passage openings being so located that the one nearer the end of the cylinder bore toward which the piston travels is covered by the piston before the other is uncovered, and separate pressure areas on said valve subjected to the compression pressures within the opposite ends of said cylinder bore, said valve being thrown by the pressure on one of said first mentioned pressure areas and by the compression pressure acting on one of said separate pressure areas.

3. In a pressure fluid motor, a cylinder having a bore, a piston reciprocable therein, and fluid distribution means for supplying pressure fluid to and exhausting fluid from said cylinder bore for effecting reciprocation of said piston including an automatic pressure fluid actuated fluid distributing valve, passage means controlled by said valve for supplying pressure fluid to the opposite ends of said cylinder bore, a centrally located exhaust port for said cylinder bore, and means for throwing said valve a substantial interval prior to the opening of the cylinder exhaust during each piston stroke including a pressure area on each end of said valve and means for supplying pressure fluid at a controlled rate to each of said pressure areas, exhaust passages communicating with said pressure areas and opening into said cylinder bore at opposite sides of said exhaust port at points each spaced longitudinally of the cylinder bore a substantial distance from said exhaust port, said exhaust passage openings being so located that the one nearer the end of the cylinder bore toward which the piston travels is covered by the piston before the other is uncovered, said exhaust passages of sufficient cross sectional area to effect free communication between said pressure areas and said cylinder bore, and separate pressure areas on opposite ends of said valve, one subjected to the compression pressure within one end of said cylinder and the other subjected to the compression pressure within the opposite end of said cylinder, said valve being thrown by pressure fluid supplied to one of said first mentioned pressure areas and by the compression pressure acting on one of said separate pressure areas.

4. In combination, in a motor, a cylinder having a bore, a piston reciprocable in said bore, an exhaust for said cylinder overrun by said piston, fluid distribution passages leading to the opposite ends of the cylinder, a pressure fluid supply, and means for connecting said pressure fluid supply alternately to the distribution passages including a valve having oppositely directed surfaces of equal area thereon each having a continuously open connection with the pressure supply, and vent passages connecting said areas to said cylinder bore at opposite sides of said cylinder exhaust, said vent passages communicating with the cylinder bore at points spaced a substantial distance longitudinally of the cylinder bore from said cylinder exhaust, said piston cutting off communication of said vent passages with said cylinder bore simultaneously during a portion of each of its strokes whereby the pressure built up on one of said valve areas effects

a throwing of the valve as soon as one of said vent passages is uncovered and at a substantial interval prior to the opening of said cylinder exhaust.

5. In a pressure fluid motor, the combination comprising a cylinder having a bore, a piston reciprocable therein, a piston-controlled exhaust for said cylinder bore, means providing a valve chamber, distribution passages leading from said chamber respectively to the opposite ends of the cylinder bore, a pressure fluid supply, a fluid actuated fluid distributing valve movably mounted in said valve chamber for alternately connecting said distribution passages with said supply, said valve having a body provided with an annular flange and presenting equal opposed pressure areas at its opposite ends, relatively restricted passages means for continuously supplying pressure fluid to said equal opposed pressure areas on said valve at the opposite ends of said valve body, said valve flange having opposed pressure areas alternately subjected to compression pressure built up within the ends of the cylinder bore by the piston, and pressure reducing passages for said equal opposed pressure areas connected to the cylinder bore at points spaced longitudinally of the cylinder bore a substantial distance from said cylinder exhaust, whereby said valve is thrown by the combined action of line pressure and compression pressure a substantial interval prior to the opening of the cylinder bore exhaust during each piston stroke.

6. In combination, in a motor, a cylinder, a piston reciprocable therein, a piston-controlled exhaust for said cylinder, fluid distribution passages opening into each end of said cylinder, a pressure fluid supply, and means for controlling the connection of said supply alternately to the distribution passages including a valve controlling said distribution passages and having an annular flange intermediate its ends and end body portions at opposite sides of said flange, means for subjecting said end body portions to different

pressures in different positions of the motor piston including restricted passage means for delivering fluid continuously to said end body portions, said annular valve flange having its opposite sides subjected to compression pressure built up in the cylinder ends by the piston, and larger vent passage means communicating with said cylinder at points spaced longitudinally thereof a substantial distance from said cylinder exhaust and intermittently controlled by the motor piston for alternately reducing the pressure on said end body portions, whereby the valve is thrown a substantial interval prior to the opening of the cylinder exhaust during each piston stroke.

7. In combination, in a pressure fluid motor, a cylinder, a piston reciprocable therein, a piston-controlled exhaust for said cylinder, fluid distribution passages opening into each end of said cylinder, a pressure fluid supply, and means for controlling the connection of said fluid supply alternately to said distribution passages including a fluid distributing valve controlling said distribution passages and having an enlarged annular flange intermediate its ends and opposite end body portions providing substantially equal opposed pressure areas at opposite sides of said flange, and means for subjecting said opposed pressure areas of said end body portions to different pressures in different positions of said motor piston including relatively restricted passage means for delivering fluid constantly to said opposed pressure areas and relatively larger vent passage means communicating with the cylinder at points spaced longitudinally thereof a substantial distance from said cylinder exhaust and intermittently controlled by said motor piston for reducing the pressure on said pressure areas of said end body portions, whereby said valve is thrown a substantial interval prior to the opening of said cylinder exhaust during each piston stroke.

FRANK E. SINCLAIR.
